CENTRIFUGAL PUMP

Walter J. Gear, Madera, Calif., assignor of one-half to Glenn M. Freeman, Madera, Calif.

Application August 5, 1938, Serial No. 223,344

3 Claims. (Cl. 103—111)

This invention relates to centrifugal pumps of the single inlet type adapted for dredging and conveying solids such as sand and gravel.

The primary object of the present invention is to provide a simple and highly efficient pump of the above kind which will have a long period of continued usefulness, that will not require priming, and whose operation requires the expenditure of a minimum amount of power.

More particularly, the present invention contemplates the provision of a pump of the above kind wherein most of the wear is limited to the peripheral wall of the pump casing, means being provided to keep the drive shaft bearing and the space between the impeller and the sides of the pump casing clear of the sand and other solid so as to not be submitted to the abrading action thereof.

Other objects and features of the present invention will become apparent from the following description when considered in connection with the accompanying drawing.

In the drawing:

Figure 1 is an edge elevational view of a centrifugal pump constructed in accordance with the present invention, the pump being mounted upon a suitable support and provided with suitable driving means.

Figure 2 is a side elevational view of the pump looking toward the left of Figure 1.

Figure 3 is an enlarged transverse section taken substantially on line 3—3 of Figure 2; and

Figure 4 is a view of the impeller partly in side elevation and partly broken away and in section, as seen looking toward the right side of the impeller as shown in Figure 3.

Referring in detail to the drawing, the present centrifugal pump includes a casing composed of pan-shaped half sections 5 and 5a, flanged along their adjacent edges as at 6 and 6a and having such flanges bolted together as at 7. The casing has a peripheral outlet half of which is formed integral with each of the respective casing sections as at 8 and 8a. Formed integral with the casing section 5a is a tubular inlet 9 disposed axially of the casing, and formed integral with the casing section 5 is a tubular housing 10 for the impeller shaft 11 which is journaled at its inner end in a suitable bearing 12 mounted in the housing 10. The section 5a of the casing is formed with an inwardly projecting flange 13 in surrounding relation to the inlet passage, and the area of the latter passage is somewhat smaller than that of the peripheral outlet for a purpose which will presently be explained. The central

portion of the casing sections 5 and 5a are provided with a series of apertures or small openings 14 and 14a adjacent and in partially surrounding relation to the inlet 9 and housing 10, for a purpose which will also be presently described.

The present pump further includes an impeller or rotor which includes two spaced disks 15 and 15a rigidly connected by impeller blades 16 which incline outwardly and backwardly with respect to the rotation of the impeller as illustrated clearly in Figure 4, so as to effectively draw the conveyed material inwardly through the inlet 9 and force the same outwardly to the peripheral wall of the casing for ultimate passage outwardly through the casing outlet 8, 8a. The disk 15 has a central hub 17 to which the inner end of drive shaft 11 is secured, and said disk 15 is further provided with a series of openings 18 directly adjacent and surrounding the hub 17 inwardly of the blades 16. Disk 15a has a relatively large central opening 19 and is provided in surrounding relation to this opening with an outwardly projecting flange 20 that surrounds the inlet flange 13 in spaced relation to the latter and to the adjacent side of the pump casing. The bearing 12 maintains the disk 15 in proper spaced relation to the opposite side of the pump casing as shown clearly in Figure 3.

Provided on the other sides of the disks 15 and 15a are further narrower blades 21 and 21a which are inclined outwardly and forwardly with respect to the direction of rotation of the impeller, as is also clearly shown in Figure 4. These blades 21 and 21a extend from the outer periphery of the impeller to a point outwardly of the openings 18 of disk 15 and the flange 20 of disk 15a, and their purpose is to direct the clear water which enters the casing through the small side apertures 14 and 14a, inwardly through the openings 18 of disk 15 and inwardly to the central opening 19 of disk 15a. In this way, the bearing 12 is kept clear of sand and other solids, and likewise with respect to the spaces between the sides of the pump casing and the sides of the impeller. These parts are thus not subjected to material wear by reason of the abrading action of these solids, and the latter are kept within the impeller so that the only portion of the pump subjected to a great amount of wear and abrading action from the solids is the peripheral wall of the casing. This peripheral wall is composed of outwardly converging wall portions and preferably lined with wear-resisting material such as removable liner plates 22 and 22a of hard metal which may be readily renewed from time to time.

as found necessary. It will thus be apparent that the pump will have a relatively long continued period of usefulness. The outlet of the pump is made of greater area than the inlet so as to take care of the additional water drawn in through the openings 14 and 14a and delivered to the outlet along with the water and solids drawn inwardly through the inlet 9. In use, the pump is wholly or partially submerged so that the water may enter the openings 14 and 14a and partly or wholly fill the casing so that the pump will not require priming. It has been found that a pump of this construction is highly efficient in operation and requires the expenditure of a very small amount of power to operate the same. The pump may be mounted on a suitable support 23 by fastening the drive shaft housing 10 thereto as at 24, the drive shaft 11 projecting at the end of the housing 10 which is uppermost in use of the pump for being operatively connected to a driving motor by any suitable means such as a belt gearing including a pulley 25 secured on this projecting end of shaft 11.

From the foregoing description, it is believed that the construction and operation, as well as the advantages of the present invention will be readily understood and appreciated by those skilled in the art. Minor changes in the specific details illustrated and described, are contemplated within the spirit and scope of the invention as claimed.

What I claim as new is:

1. A centrifugal pump adapted to be at least partially submerged in use and comprising a casing having a peripheral outlet and provided at one side with an axial inlet, an impeller arranged within the casing including spaced disks connected by tangential blades inclining outwardly and backwardly with respect to the direction of rotation of the impeller, said disks being spaced from the sides of the casing and having further tangential blades on the outer sides thereof inclined forwardly with respect to the direction of rotation of the impeller, said casing further having relatively small water inlet openings through the sides thereof adjacent the center of the same, and means permitting passage of water through said disks inwardly of said blades, said water inlet openings being in the portion of the casing adja-

cent said further blades so that the latter may force clear water inwardly toward the axis of the pump.

2. A centrifugal pump adapted to be at least partially submerged in use and comprising a casing having a peripheral outlet and provided at one side with an axial inlet, an impeller arranged within the casing including spaced disks connected by tangential blades inclining outwardly and backwardly with respect to the direction of rotation of the impeller, said disks being spaced from the sides of the casing and having further tangential blades on the outer sides thereof inclined forwardly with respect to the direction of rotation of the impeller, said casing further having relatively small water inlet openings through the sides thereof adjacent the center of the same, said water inlet openings being in the portion of the casing adjacent said further blades so that the latter may force clear water inwardly toward the axis of the pump, the side of the casing opposite that provided with the inlet having a bearing, and a drive shaft for the impeller journaled in said bearing and attached to the adjacent one of said disks, the last-named disk having openings therethrough in surrounding adjacent relation to said shaft, the other disk having an outward flange and a central opening surrounded thereby considerably larger than said inlet, and an inwardly projecting flange extending into the last-named flange but spaced from the latter in surrounding relation to said inlet.

3. A centrifugal pump adapted to be at least partially submerged in use and comprising a casing having a peripheral outlet and provided with an axial inlet in one side thereof, an impeller arranged in the casing and including spaced disks connected by blades, means permitting passage of water through said disks inwardly of said blades, the sides of the casing having perforations adjacent the center thereof for the admission of clear water, and further blades on the outer sides of said disk for forcing said clear water inwardly toward the axis of the pump and between the disks, said perforations being in the portion of the casing adjacent said further blades so that the latter may force clear water inwardly toward the axis of the pump.

WALTER J. GEAR.
